UNITED STATES PATENT OFFICE.

OSMOND A. OSMONDSON, OF CHICAGO, ILLINOIS.

HAND FEED FOR DRILL PRESSES.

Application filed January 8, 1921. Serial No. 435,963.

To all whom it may concern:

Be it known that I, OSMOND A. OSMONDSON, a citizen of the United States, residing at Chicago, in the county of Cook and State of Illinois, have invented a new and useful Hand Feed for Drill Presses, of which the following is a specification.

This invention relates to hand feeds for drill presses, one of its objects being to provide a hand wheel or its equivalent for operating change speed mechanism of novel construction whereby the drill bit can be quickly returned from the work, can be rotated at a high speed during light drilling and facing and can be caused to rotate at a greatly reduced speed and with proportionately increased power of the operating wheel while heavy drilling is taking place.

A still further object is to provide a hand feed which can be quickly placed in neutral position so as to allow a counterbalance to lift the drill bit without operating the handle or hand wheel.

While various devices for producing the results herein mentioned have been devised, they have not been found practical because of their cumbersome construction, complex mechanism, and the awkward manipulation necessary. An object of the present invention is to simplify and render more compact a mechanism of this character which is under instant control and which practically eliminates all danger to the operator.

A further object is to provide mechanism in a hand feed which does not require the use of the speed reduction except while the drill bit is being actually directed into heavy work, it being unnecessary to use the speed reduction in raising or lowering the spindle, as in most mechanism of this type.

A still further object is to provide a safety latch whereby the shifting lever of the change speed mechanism can be held positively against accidental movement during the operation of the drill bit.

A still further object is to provide hand feed mechanism having a novel arrangement of cooperating gears and coupling plungers by the use of which the main shaft of the feed can be rotated in either direction for raising and lowering the spindle of the drill bit.

With the foregoing and other objects in view, which will appear as the description proceeds, the invention resides in the combination and arrangement of parts and in

the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a plan view of a portion of a drill press having the present improvements combined therewith.

Figure 2 is a central vertical section through the parts shown in Figure 1.

Figure 3 is a section on line 3—3, Figure 2.

Figure 4 is an elevation of the internal gear and its housing member.

Figure 5 is an elevation of the coupling disk.

Figure 6 is a perspective view of the latch.

Referring to the figures by characters of reference 1 designates the head carried by the column 2 of a drill press, said head being provided with a guide sleeve 3 in the inner surface of which is formed a guideway 4 adapted to receive the rack which is ordinarily used on the drill spindle of the press.

The head 1 is formed with a bearing 5 at one side while engaging the other side of the head is a hollow extension 6 formed with or secured to a shallow cylindrical housing 7 concentric therewith. Openings 90 for the reception of grease can be provided wherever desired in this housing and can be normally closed by screw plugs 8.

Journalized in the bearing 5 and the portion 1^a of head 1 and extending transversely through the head 1 is a shaft 9 to which is secured a gear 10 mounted for rotation in the head and adapted to project into the guideway 4 so as to mesh with the rack on the drill spindle hereinbefore referred to. Formed on or secured to one end of the shaft 8 is a boss 11 adapted to rotate freely within the extension 6 and provided with a central socket 12. This boss extends from one face of a disk 13 constituting a coupling member and which disk has an annular flange 14 on the inner surface of which is provided an internal gear 15. This disk 13 is adapted to work in close proximity to one face of the inner wall of housing 7 and spaced openings 16 are provided in this disk for the purpose hereinafter set forth.

Secured to the open side of the housing 7 is a cover plate 17 having a central hollow extension 18 in which is located a cylindrical block 19. A shifting lever 20 extends from this block and projects through a cam slot 21 formed in and extending partly around the extension 18.

Arranged within the extension 18 and bearing against the block 19 is a boss 22 extending from the center of a disk 23 which forms one wall of a cylindrical cage mounted for rotation in the space surrounded by the flange 14. Another disk 24 forms the other wall of this cage and the two disks 15 are connected at desired intervals by rivets, bolts or the like indicated generally at 25 and which are provided with spacing sleeves 26. Slidably mounted in the disks 23 and 24 near the peripheries thereof and at desired intervals are coupling pins or plungers 27. Each of these pins has a collar 28 thereon and the collars on certain of the pins are adapted to bear against the disk 23 while the collars on the remaining pins are adapted to bear against the disk 24. Springs 29 are mounted on these pins, each spring bearing at one end against the collar on the pin and at its other end against one of the disks. Thus the springs all serve to hold the collars normally projected against the disks adjacent thereto, with one end of each pin flush with the outer surface of one disk while the other end of the pin, which is nearest the collar on the pin, is normally projected beyond the outer surface of the other disk.

An annular rib 30 is formed on the inner face of the cover plate 17 and is provided at desired intervals with recesses 31 into which, under certain conditions, certain of the pins or plungers 27 will project.

A shaft 32 is extended through the block 19 and boss 22 and is journaled in socket 12 and in the end 18^a of extension 18. This shaft is provided at its outer end with any suitable operating means such as a hand wheel 33. Secured to this shaft 32 and adapted to rotate therewith between the disks 23 and 24 is a pinion 34 which meshes with intermediate gears 35 journaled on bearing pins 36 carried by the disks. These gears 35 mesh with additional gears 37 journaled on bearing pins 38 carried by the disks and said gears 37 project outwardly beyond the cage formed by the disks and mesh with the internal gear 15. A collar 39 is secured to the shaft 32 between the other end of extension 18 and the block 19.

It will be understood that when the lever 20 is in an intermediate position within the cam slot 21 the block 19 has thrust the boss 22 a sufficient distance to disengage the pins 27 from the recesses 31 without, however, moving said pins into the openings 16. Obviously when the parts are thus located the

gear 10 can rotate with shaft 8 without causing rotation of the hand wheel 33 because the internal gear 15 will cause the cage to rotate therewith at such speed as to travel around gear 34 without operating it. Obviously, therefore, a lifting weight, not shown, but which has heretofore been used in drill presses, will operate automatically to lift the spindle of the drill without rotating the hand wheel 33, such upward movement being rapid so that a considerable saving of time is effected over those machines which require manual operation to lift the spindle.

When it is desired to feed the spindle of the bit downwardly at a high speed, and which operation can be effected safely in light work, etc., the lever 20 is thrown to the right as viewed in Figure 1. This is due to the fact that when the lever is thus moved it cooperates with the wall of the cam slot so as to move the cage outwardly and cause certain of the pins 27 to engage certain of the openings 16. Thus the two shafts 32 and 8 are locked together by the joint formed by the internal gear 15 and the cage with the result that when shaft 32 is rotated, the shaft 8 will be also rotated at the same speed and allow for a quick up or down movement of the spindle.

By moving the lever 20 to its other extreme position the cage is shifted so as to bring the pins 27 into certain of the recesses 31, thereby locking the cage to the stationary cover plate 17. As the cage is thus held against rotation, the rotation of the shaft 32 and gear 34 will result in the transmission of motion at a reduced speed to the internal gear 15 and shaft 8, thus causing the spindle to be raised or lowered at a greatly reduced speed and rendering the mechanism especially adapted for use in heavy work where the resistance to the action of the drill is considerable.

By providing the latch indicated at 40 and which is pivotally connected to the cover plate 17, the lever 20 can be held in one extreme position while the mechanism is set for light work.

Obviously by utilizing mechanism such as described there is no danger of the feed mechanism becoming released unexpectedly and injuring operators adjacent thereto.

Obviously various changes in the construction of certain of the parts of the mechanism can be made within the scope of this case. For example the pins or plungers can be made of shapes other than those illustrated and the proportions of the various parts can be changed to meet conditions. Wherever desired anti-friction bearings may be provided.

What is claimed is:

1. In a hand feed for drill presses the combination with a spindle actuating gear

and an operating member, of change speed mechanism for transmitting motion from said member to the gear, said mechanism including an internal gear, a cage, and a train 5 of gears in the cage and meshing with the internal gear, means under the control of the operator for shifting said cage to one position to reduce the speed of the driven gear, to another position to insure equal speed 10 of said member and gear and to a third position to uncouple the drive connection between said member and gear, and means for securing said shifting means in one of its positions.

15 2. In a hand feed for drill presses a spindle actuating gear, an internal gear revolvable with said actuating gear, an operating member, a stationary cover plate, a shift- 20 able cage surrounded by the internal gear, a train of gears movable with the cage and meshing with the internal gear, one gear of said train being revolvable with the operating member, means for shifting the cage, and means operated by the shifting of the 25 cage for coupling said cage to the cover plate or to the internal gear.

30 3. In a hand feed for drill presses, aligning shafts, an operating member connected to one shaft, a power transmitting member 35 connected to the other shaft, a disk revolvable with one of the shafts, a stationary cover plate, an internal gear carried by the disks, a cage interposed between the disk and cover plate, a train of gears carried by the 40 cage and meshing with the internal gear, said train including a gear upon the shaft of the operating member, coupling members carried by the cage, and means for shifting the cage in one direction to couple it to the cover plate, and in the opposite direction to 45 couple it to the disk, said cage when in intermediate position being uncoupled from the plate and disk.

45 4. In a hand feed for drill presses, aligning shafts, a power transmitting member

connected to one of the shafts, an operating member connected to the other shaft, a disk revolvable with the shaft of the power transmitting member, an internal gear carried by the disk, a stationary member, a cage interposed between the disk and stationary member, a train of gears movable with the cage and meshing with the internal gear, said train including a gear upon the shaft of the operating member, spring pressed coupling pins normally projected from opposite sides respectively of the cage, means under the control of the operator for shifting the cage to project the pins into engagement with the disk or with the stationary member.

50 5. A hand feed for drill presses including aligning shafts, a gear upon one shaft, an operating member on the other shaft, a disk revolvable with the gear shaft and having openings, an internal gear movable with 55 the disk, a stationary member having recesses, a cage interposed between the stationary member and the disk, a train of gears movable with the cage and meshing at one end with the internal gear, said train including a gear upon the shaft of the operating member, spring pressed coupling pins 60 slideable within the cage and normally projecting from opposite faces respectively of the cage, said stationary member having a 65 cam slot therein, and means under the control of the operator and working in the slot for shifting the cage to project the coupling pins into the openings in the disk or into the recesses in the stationary member, said cage 70 being movable to an intermediate position with its pins uncoupled from both the disk and stationary member.

In testimony that I claim the foregoing as my own, I have hereto affixed my signature in the presence of two witnesses.
